Application August 10, 1937, Serial No. 70,971

Term of patent 3½ years

To all whom it may concern:

Be it known that we, Wallace K. Harrison and Jacques Andre Fouilhoux, citizens of the United States, residing respectively at 237 East 81st Street, New York, N. Y., and Short Hills, N. J., have invented a new, original, and ornamental Design for a Plaque, of which the following is a specification, reference being had to the accompanying drawing, forming a part thereof, in which Fig. 1 is a plan view of a plaque embodying our new design; Fig. 2 is a cross-sectional view taken along the line 2—2 of Fig. 1.

We claim:

The ornamental design for a plaque as shown.
